SECRECY SIGNALING SYSTEM, METHOD,
AND APPARATUSRobert M. Sprague, Manhasset, N. Y., assignor
to Press Wireless, Inc., Chicago, Ill., a corpora-
tion of Delaware

Application November 19, 1943, Serial No. 510,943

19 Claims. (Cl. 179—1.5)

This invention relates to secrecy signaling systems and more especially to secrecy systems of the frequency scrambling type.

A principal object is to simplify and improve the secrecy system and apparatus disclosed in my prior application Serial No. 410,450, filed Sept. 11, 1941.

Another object is to provide a frequency scrambling arrangement for secrecy systems and the like, wherein the band width required for transmitting the scrambled message is approximately the same as the frequency band of the original signals.

Another object is to provide a simplified and improved secrecy system which is useful over radio links as well as over wire lines.

Another object is to provide a system of secrecy transmission which is well suited for commercial wire line communication systems.

A feature of the invention relates to a modulating arrangement for frequency scrambling systems whereby the number of possible scrambling combinations is materially increased without increasing the band width required for transmission.

Another feature relates to a secrecy system of the general type disclosed in my prior application Serial No. 410,450, but wherein only a single variable frequency modulator is required at the transmitter and a corresponding single variable frequency modulator is required at the receiver.

Another feature relates to the method of using haphazard recorded frequencies to control a single variable frequency modulator while achieving the scrambling power heretofore requiring two or more variable oscillators.

A further feature relates to a frequency scrambling system of the type employing haphazard frequency recordings as modulator controls, wherein a substantial reduction is obtained in the band of recorded haphazard frequencies.

A still further feature relates to the novel organization, arrangement and relative interconnection of parts which cooperate to produce a simplified and "break-proof" secrecy signaling system.

Other features and advantages not specifically enumerated will be apparent after a consideration of the following detailed descriptions and the appended claims.

In the drawings which are illustrative of one preferred embodiment,

Fig. 1 is a schematic block diagram of a secrecy signaling system according to the invention.

Fig. 2 is a chart showing the relation between

original signal frequency and the output or scrambled frequency for three arbitrary values of the haphazard oscillator frequency.

Fig. 3 is a chart showing the relation between input and output frequencies for the various modulator stages, and also the relation between signal input frequency and output frequency for the over-all modulator stages.

Fig. 4 is a schematic diagram of a recording blank arrangement from which are derived the variable oscillator frequencies.

Fig. 5 is a modification of Fig. 4.

Referring to Fig. 1 the numeral 1 represents schematically any well-known form of signal generator such for example as a microphone or other voice frequency source. The original voice frequencies are passed through a low-pass filter 2 to limit the frequency range to some predetermined band e. g. 0—1800 cycles. This 0—1800 cycle band is then passed through another filter network 3 which is logarithmic between input and output so that the fundamental and harmonics of the voice frequencies are equalized in power and this equalization is spread over the 0—1800 band. The signals from filter 3 are divided into two paths each including a double-balanced modulator 4, 5 of the type disclosed in application Serial No. 501,928, filed Sept. 11, 1943. Modulator 4 is supplied with an 1800 cycle carrier from a suitable source 6, while modulator 5 is supplied with a 3600 cycle carrier from source 7. If desired, the 1800 and 3600 cycle carriers can be derived from the same source.

In the output of modulator 4 there appear substantially only the sum and difference frequencies between the 1800 cycle carrier and the input frequencies from filter 3. Likewise in the output of modulator 5 there appear substantially only the sum and difference frequencies between the 3600 cycle carrier and the input frequencies from filter 3. Modulator 4 is followed by an 1800 cycle low-pass filter so that there appear at the output of filter 8 only the difference frequencies from modulator 4. Likewise modulator 5 is followed by a 3600 cycle low-pass filter whereby there appear at its output only the difference frequencies from modulator 5. The outputs of filters 8 and 9 are then recombined thus giving in the common output, voice frequencies in two bands, the original 0—1800 cycle band from filter 3 being now transposed to 3600—1800 and 1800—0.

The transposed and recombined signal from the first modulator stage #1 is then fed into modulator stage #2 including a double balanced modulator 10 similar to modulators 4, 5. Modulator

10 is supplied with a carrier frequency from source 11 which frequency is variable over the band 3800—5400 cycles but at a haphazard rate. Consequently the dual voice frequency band 3600—1800 and 1800—0 from modulator #1 is changed to the sum and difference frequencies between the carrier from source 11 and the frequencies from stage #1. The output of modulator 10 is followed by a 3600 cycle low-pass filter 12 which eliminates all the sum frequencies from modulator 10 and passes substantially only the difference frequencies below 3600 cycles.

The frequencies from stage #2 are fed into a modulator stage #3 comprising the double balanced modulator 13 similar to modulator 10. Modulator 13 is supplied with a 3600 cycle carrier from source 14, and modulator 13 is followed by an 1800 cycle low-pass filter whereby only the difference frequencies from modulator 13 are passed. The scrambled signal from filter 15 is then transmitted to the receiving station over any suitable transmission link 16 which may be a wire telephone line.

At the receiver the received scrambled frequencies are passed through successive stages which are identical with the stages #1, #2 and #3. In the drawings the parts at the receiver which correspond to those at the transmitter bear the same designation numeral. At the receiver the filter 3b is the converse of the filter 3 at the transmitter so as to restore the original power relations in the fundamental and harmonics of the signal frequencies, and of course the microphone is replaced by a suitable voice-frequency recorder or reproducer 1b. It will be understood that the variable frequencies from modulator 11b at the receiver are synchronized in any suitable manner with the frequencies from modulator 11 at the transmitter so that at any given instant each modulator supplies the identical frequency to its corresponding modulator 10 or 10b.

One preferred manner of deriving the variable 3800—5400 cycle carriers at the transmitter and receiver is schematically shown in Fig. 4. A previously made identical phonographic recording of the haphazard frequencies on two phonograph blanks 17 and 17b is used respectively at the transmitter and receiver. These phonograph records are rotated by respective motors 18 and 18b which are maintained in synchronism in any well-known manner. Associated with each record is a pair of phonograph pick-ups 19, 20 whose relative spacing is fixed, but whose joint position with respect to the record 17 can be varied as desired. By suitable arrangements as described in my said prior application Serial No. 410,450, the corresponding pick-ups 19b and 20b at the receiver can be located at the proper orientation with respect to the record at the receiver. The haphazard frequencies from the two pick-ups 19, 20 are added by means of a double balanced modulator 21 similar to modulator 4 and the modulator output is passed through a suitable high-pass filter for passing the sum frequencies from modulator 21. The same applies to the pick-ups 19b, 20b.

In my prior application Serial No. 410,450, filed Sept. 11, 1941, two variable frequency modulators are required at the transmitter, and two similar synchronized variable frequency modulators are required at the receiver. By using the method of deriving the single variable frequency above described, the recording frequency of the scrambling track in each phonograph rec-

ord is reduced by approximately 50% and permits doubling the playing time of the records. The same number of scrambling combinations are afforded as are afforded with the system of my prior application even though the phonograph records rotate at the same speed as the rotation of the records in the prior application. However, by rotating the records above described at half the speed required in the prior application, the number of scrambling conditions is squared.

Fig. 2 shows in graph form the relation between the original signal voice frequency and the output frequency from the filter 15 or filter 15b. The full-line graphs A show the relation when the oscillators 11 and 11b, are each delivering 3800 cycles. The dotted-line graphs B show the relation at a carrier frequency of oscillators 11 and 11b of 4600 cycles; while the dot-dash line graph C shows the relation at a frequency of 5400 cycles.

The graphs of Fig. 3 show the individual input and output frequencies for the three modulator stages at an instant when the oscillators 11 and 11b are delivering for example 3800 cycles. In this figure, the full-line graph D shows the relation between the input and output frequencies of modulator stage #1. The dashed-line graph E shows the relation between the input and output frequencies of the modulator stage #2. The dot-dash line graph F shows the relation between the input and output frequencies of modulator stage #3. The dotted line graphs G show the overall relation between the input frequency to stage #1 and the output frequency at stage #3. It will be noted that the graphs G correspond to the graphs A of Fig. 2. A similar series of graphs for different haphazard carrier frequencies of the oscillators 11 and 11b will show that the output frequency of the third stage is confined to the 0 to 1800 cycle band, notwithstanding the scrambling and successive modulations to which the input signals have been subjected.

If there is any disturbance produced by an irregular motion of the record 17, this difficulty is overcome in the following manner (Fig. 5). Assume that the frequencies recorded on the variable frequency track range between 1,900 and 2,700 cycles at some haphazard rate. Instead of adding these frequencies directly the output from one of the pick-up arms e. g., pick-up 19, is beat in the modulator 25 against a fixed frequency of 4,600 cycles from source 26, and the differency frequency taken therefrom. When the pick-up arm 19 is scanning 1,900 cycles, the output from the modulator 25 delivers 2,700 cycles (4600—1900), and when the pick-up arm 19 is scanning 2700 cycles, the output from the auxiliary modulator is 1,900 cycles. Thus, the range of frequencies is the same. The output of this auxiliary modulator 25 is then added to the output of the other unaffected pick-up arm 20 and as before, the sum output frequencies of from 3,800 to 5,400 cycles result. Now the variable frequency modulator is receiving the same range of frequencies as before but the following has been accomplished. When the drum or turntable increases in frequency due to inaccurate gears, the output frequencies from each of the pick-up arms 19 and 20, increase proportionately. The output frequency of the unaffected arm 20 varies, of course, but the output frequency of the auxiliary modulator 25 decreases when its input frequency increases. Thus, the change of frequency of the

sum is now much less affected by changes in drum or turntable speed.

An example shows this improvement. Assume that each pick-up arm was scanning 1,900 cycles and assume that the drum or record carrier rotation increased 10% in speed, then the output from each pick-up amplifier would increase from 1,900 to 2,090 cycles per second, but the output from the auxiliary modulator 25 would decrease from 2,700 to 2,510 cycles per second. Upon addition the sum frequency would be 4,600 cycles (2510—2090) as against 4,600 cycles, had no speed increase been present (1,900 plus 2,700). Thus, a change in drum speed has produced absolutely no change in sum frequencies. Consider the other extreme where one pick-up arm is scanning 1,900 cycles and the other pick-up arm is scanning 2,700 cycles. Under a 10% speed increase, the unaffected 1,900 cycle arm is delivering 2,090 cycles while the 2,700 cycles arm has increased to 2,970 cycles and output of the auxiliary modulator is 1,630 cycles (4600—2970). Thus, the result is a sum frequency of 3,720. No frequency change due to gear inaccuracies would have delivered an output frequency of 3800 cycles. Thus, a 10% change in drum speed has produced only an 80 cycle change in sum frequency. Thus, we see that this system under this extreme condition gives an improvement of 5.75 to 1 (460 to 80), and under the other extreme condition, it gives an infinitely improved condition. Therefore, we may assume that the average improvement is at least 10 to 1 and the gear requirements and tolerances are therefore reduced by the same amount. It will be understood that while a record medium in the form of a phonograph disc and a turntable are disclosed that any other well-known form of record medium and pick-up may be employed, for example a photographic sound film and associated scanning equipment, or a magnetized wire or band record.

It will be understood that in connection with the modification of Fig. 5 that identical means are used at the receiving end as shown.

While certain particular embodiments of the invention have been described, it will be understood that various changes and modifications may be made therein without departing from the spirit and scope of the invention.

What is claimed is:

1. The method of secret signal transmission which comprises, transposing the original frequency succession into a different frequency succession occupying a band width greater than that of the original frequencies, generating a haphazardly variable frequency carrier, modulating said carrier by said other frequencies, selecting one side band of the modulations, and remodulating each side band to restore the original band width but without restoring the original frequency succession.

2. The method of secret signal transmission which comprises, transposing the signal frequencies into other frequencies occupying a band approximately twice the width of the original band, modulating said transposed band on a haphazardly variable carrier whose frequency is higher than the width of the transposed band, the frequency excursion of said variable carrier being less than the band width of the original frequencies, selecting one side band from the modulated variable carrier, remodulating the selected side band on another carrier of lower frequency than said variable carrier to restore the

original band width without restoring the original frequency successions.

3. The method of secret signal transmission which comprises, confining the original signals to a band e. g., f_0-f_1 , modulating said band on a carrier of frequency f_1 , simultaneously modulating said band on another carrier of frequency $n f_1$, selecting only the difference frequencies from each modulated carrier, combining said difference frequencies, modulating a haphazardly varying frequency carrier by said combined difference frequencies, selecting from said modulated variable frequency carrier the difference frequencies, modulating the last-mentioned selected frequencies on a carrier of $n f_1$, and selecting from the last-mentioned modulated carrier the difference frequencies.

4. The method according to claim 3 in which said variable frequency carrier is varied at a haphazard rate but over a frequency band whose width is less than f_0-f_1 .

5. The method of secret signal transmission of an original signal frequency spectrum of a predetermined band width which comprises, subjecting the signals to successive carrier modulations, one of which is of the haphazardly variable carrier type whereby the final signals have a frequency spectrum of approximately the same width as the original signals but with at least a portion of the original frequency spectrum scrambled.

6. The method of secret signal transmission of an original signal frequency spectrum of a predetermined band width which comprises, equalizing the power in all frequencies of the signal band, subjecting the signal frequencies to at least three successive carrier modulation stages, the first stage producing an inverted frequency spectrum the band width of which is a multiple of the original spectrum, the second stage producing a scrambled frequency spectrum, and the third stage producing a scrambled frequency spectrum of substantially the same width as the original band.

45 7. The method of secret signal transmission of an original signal frequency spectrum which comprises, subjecting said spectrum at a transmitter to successive carrier modulations including modulation of a haphazardly variable carrier, one of which is a varying frequency carrier stage to produce a frequency spectrum for transmission of substantially the same band width as the original signals but with the frequencies scrambled, receiving the last-mentioned band and subjecting 50 it to successive carrier modulations similar to those at the transmitter with the varying carrier at the receiver synchronized with the varying carrier at the transmitter to reproduce the original frequency spectrum.

60 8. In a secret signaling system, a source of signal frequency spectrum having a predetermined band width, means to subject said spectrum to successive frequency changing stages, one of which is of the haphazardly varying carrier type for scrambling the frequencies, and means to select from the last modulation stage a frequency spectrum of substantially the same band width as the original spectrum but with the frequencies scrambled.

65 9. In a secret signaling system, a source of signal frequencies within a predetermined spectrum, three successive frequency-changing stages for said spectrum, the first stage having means to expand the spectrum to a multiple of the original, the second stage having means to scramble

the signals from the first stage in a haphazard manner, and the third stage having means to restore the band width of the scrambled frequencies to that of the original band width.

10. A secret signaling system according to claim 9 in which the original spectrum has an upper frequency of f_1 and the said first stage comprises a pair of modulators one of which is supplied with a carrier of approximately f_1 and the other of which is supplied with a carrier approximately nf_1 , means to select from the first modulator the spectrum below f_1 , means to select from the second modulator the spectrum below nf_1 , means to combine the two selected spectrums; the said second stage comprises a modulator upon which said combined spectrums are impressed and a source of haphazardly varying carrier connected thereto, said carrier having a band width which is less than that of the original spectrum but with its lower frequency limit above nf_1 , and means to select from said second modulator stage the spectrum with a maximum frequency limit of approximately nf_1 ; and said third stage comprises a modulator supplied with carrier of frequency nf_1 , and means to select from its output a spectrum of substantially the same width as the original spectrum but with the frequencies scrambled.

11. A secret signaling system according to claim 9 in which the said first stage comprises, a pair of double-balanced modulators upon which the original signals are separately impressed and means to select and combine from the said pair of double-balanced modulators the difference frequencies; said second stage comprising another double-balanced modulator upon which the combined difference frequencies from the first stage are impressed, the double-balanced modulator of the second stage being connected to a source of carrier of haphazardly varying frequency and means to select from the output of said variable carrier modulator a spectrum which is approximately the same band width as the input band width; said third stage comprising a double-balanced modulator upon which the selected spectrum from the second stage is impressed and means to select from the output of said third stage a spectrum of substantially the same width as the original spectrum but with the frequencies scrambled.

12. A system according to claim 9 in which the selected spectrum from the third stage is received by a receiver having substantially the same frequency-changing stages as at the transmitter.

13. A secret signaling system comprising a source of signals of a predetermined limited frequency spectrum, and a plurality of frequency-changing stages for scrambling the original fre-

quencies while maintaining the original band width, the last-mentioned means including a carrier modulation stage which is supplied with a haphazardly varying carrier.

14. A secret signaling system according to claim 13 in which the source of haphazardly varying carrier comprises a record of frequencies having a frequency succession which is haphazard, a pair of pick-ups cooperating with said record at different portions thereof, and means to combine the signals from said pick-ups to produce a single signal of variable frequency.

15. A secret signaling system according to claim 13 in which the source of variable carrier frequency comprises a record of frequency successions varying haphazardly, a plurality of pick-ups associated with different portions of said record to produce simultaneously different frequencies, a double-balanced modulator upon which the signals from said pick-ups are impressed, and means to select one side band of the output of said double-balanced modulator.

16. Apparatus for producing a haphazardly varying frequency for secret signaling systems comprising a record medium embodying a record of haphazardly succeeding frequencies, a plurality of pick-ups associated with different portions of said record to produce simultaneously different frequencies under control of said record, and means to combine the signals from said pick-ups to produce a single signal whose frequency varies haphazardly but as a function of the records of the recorded frequencies.

17. Apparatus according to claim 16 in which a frequency inversion modulator is provided between one pick-up and the said combining means to compensate for irregularities in the movement of the record.

18. Apparatus according to claim 16 in which a difference frequency modulator is provided between one pick-up device and said combining means whereby irregularities in the movement of the record carrier are compensated for.

19. A re-entrant band shifter for an original frequency band f_1-f_3 , comprising means to shift the band to a different spectrum f_2-f_4 where f_2 is intermediate f_1-f_3 and wherein the band f_2-f_4 is wider than the band f_1-f_3 , means to restore the portion of the band f_2-f_4 which does not overlap the band f_1-f_3 to the non-overlapping portion of the band f_1-f_3 but with the frequency succession of the said restored portion different from the corresponding original portion of the band f_1-f_3 , and the resultant spectrum is of the same width as f_1-f_3 but with a different frequency succession from the said original frequency band.

ROBERT M. SPRAGUE.
